CLAIM

The ornamental design for a car dash ornament, as shown
and described.

DESCRIPTION

FIG. 1 is a top, front and side perspective view of a car dash
ornament showing my new design;

FIG. 2 is a left-side elevational view thereof;

FIG. 3 is a front elevational view thereof;

FIG. 4 is a right-side elevational view thereof; and,

FIG. 5 is a rear elevational view thereof.

The bottom view of the design is not a matter of ornamental
concern because the bottom view is obstructed by the
surface upon which the ornament is positioned. Accordingly,
this view has been omitted.
